US00D960981S

(12) **United States Design Patent** (10) **Patent No.:** **US D960,981 S**
(45) **Date of Patent:** **** Aug. 16, 2022**

(54) **DISPLAY FIXTURE**

(71) Applicant: **TARGET BRANDS, INC.**,
Minneapolis, MN (US)

(72) Inventors: **Selina Larsen**, Duluth, MN (US); **Dan Smith**, La Grange Park, IL (US);
Witold Nowak, Harwood Heights, IL (US); **Carla Fahden**, Minneapolis, MN (US); **Chad Olson**, Minneapolis, MN (US)

(73) Assignee: **Target Brands, Inc.**, Minneapolis, MN (US)

(**) Term: **15 Years**

(21) Appl. No.: **29/779,460**

(22) Filed: **Apr. 19, 2021**

Related U.S. Application Data

(62) Division of application No. 29/688,023, filed on Apr. 17, 2019, now Pat. No. Des. 919,706.

(51) **LOC (13) Cl.** **20-02**

(52) **U.S. Cl.** **D20/42**

(57) **CLAIM**

The ornamental design for a display fixture, as shown and described.

DESCRIPTION

FIG. 1 is a top and front perspective view of a display fixture, showing our new design;

FIG. 2 is a front view thereof;

FIG. 3 is a rear view thereof;

FIG. 4 is a right side view thereof;

FIG. 5 is a left view thereof; and

FIG. 6 is a top view thereof; and,

FIG. 7 is a bottom view thereof.

In the drawings, the broken lines depict unclaimed subject matter only. The bolded long dash-short dash broken lines

(Continued)

indicate the bounds of the claimed design and otherwise form no part of the claimed design.

1 Claim, 7 Drawing Sheets
